UNITED STATES PATENT OFFICE.

GEORGE A. RENDAHL, OF DENVER, COLORADO, ASSIGNOR TO DONALD P. HOGAN, OF DENVER, COLORADO.

OIL-BAFFLE FOR AUTOMOBILE-ENGINES.

1,327,779.

Specification of Letters Patent. Patented Jan. 13, 1920.

Application filed June 2, 1919. Serial No. 301,180.

To all whom it may concern:

Be it known that I, GEORGE A. RENDAHL, a citizen of the United States, residing at the city and county of Denver and State of Colorado, have invented certain new and useful Improvements in Oil-Baffles for Automobile-Engines; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in a baffle structure for automobile engines of the V-type, my object being to provide a structure of this class arranged between the inner extremities of the cylinders and the crank case, which shall efficiently perform the function of preventing an excess of oil from the crank case from entering the cylinders due to the splash of the cranks as they enter the oil of the case and the suction due to the outward stroke of the pistons.

In the absence of some efficient baffle structure, an excess of oil enters the cylinders, works past the pistons, and is burned in the explosion compartments of the cylinders, with the result that the electrodes of the ignition mechanism are fouled, and with the further result that a large amount of carbon accumulates in the cylinders.

As heretofore indicated, the object of my present invention is to overcome this difficulty, and to this end I employ a number of baffle plates, which are so constructed that their upper extremities are formed into hooks which engage the flanges of the engine block at the inner extremities of the cylinders, their lower edges being secured by a single bolt, whereby these plates are readily attachable and detachable. The plates are provided with elongated openings, which are narrowest at their opposite ends and widest in the center, being so formed as to accommodate the piston rods or stems, their special construction being such as to make the openings as small as possible and still allow the piston stems or rods to pass without interference.

Having briefly outlined my improvement, I will proceed to described the same in detail, reference being made to the accompany-

ing drawing, in which is illustrated an embodiment thereof. In this drawing:

Figure 1 is a sectional end elevation of an engine or motor of the V-type, showing my improved baffles in use. 60

Fig. 2 is a section taken on the line 2—2, Fig. 1, looking toward the right.

Fig. 3 is a section taken on the line 3—3, Fig. 1, viewed in the direction of the arrows.

Fig. 4 is a perspective view of one of my improved baffle plates, shown on a larger scale. 65

The same reference characters indicate the same parts in all the views.

Let the numeral 5 designate an internal combustion engine, or motor, of the V-type, having a crank case 6 and two sets of cylinders 7, which are inclined inwardly and downwardly from their outer extremities, as is common in this class of motors. 70

Assuming that the engine has eight cylinders, and there are four in each set, there will be two baffle plates 8 employed in connection with each set of cylinders, or four altogether, for an eight-cylinder motor. 80

Each of these baffles consists of a plate 9 having elongated openings 10 spaced to receive the piston rods or stems 12 of the pistons 13 of two cylinders 14. This plate has side members 15 extending at right angles 85 to the part 9 and corresponding in width with an end member 16, so that when the baffle is in position as illustrated in Fig. 1, the part 9 will extend inwardly beyond the inner extremities of the cylinders far enough 90 to allow the pistons to protrude slightly beyond the open ends of the cylinders. The end member 16 is provided with a hook 17, which engages a flange 18 formed on the engine block at the inner extremities of the 95 cylinders. This hook-shaped part 17 is provided with a central V-shaped part 19, which fits into the space of corresponding shape between the two cylinders with which every baffle is used, thus centering the baffle 100 and preventing any lateral movement. The lower edge of the baffle is flanged as shown at 20, the flange consisting of three parts, as the openings in the plate 9 are continued through the plate as shown at 21, the plate 105 being reinforced above the flange 20 by a metal strap 22, extending transversely of the plate and being secured thereto by suitable fastening devices 23. In addition to the connection of the hook-shaped member 17 of 110

the baffle with the flange 18 of the engine block, the baffle is secured in place by means of a single bolt, screw or other fastening device 24, which is passed through an opening 25 in the central part of the flange 20 of the baffle. Hence, when the baffle is placed in position, it is only necessary to secure it by a single fastening device 24, and when it is desired to remove the baffle, 10 it is only necessary to detach the single fastening device.

From the foregoing description, the use of my improved oil baffle structure will be readily understood.

15 When the engine is in operation, the piston stems or rods 12 move freely in the openings 10 of the baffle plates, these openings being shaped to prevent, as far as possible, the entrance of oil from the crank case into 20 the engine cylinders, due to the splash of the cranks and the suction of the pistons, as heretofore explained. By virtue of the sides 15 and the corresponding end members 16 of each baffle, the body 9 of the plate is offset 25 inwardly from the extremities of the cylinders far enough to permit the proper inward movement of the cylinder pistons, as heretofore indicated.

Attention is called to the fact that in Fig. 30 2 the baffle 8 is shown on the left-hand side, but omitted on the right-hand side.

I claim:

1. The combination with an internal combustion engine, of a baffle plate detachably applied to the engine block between the inner extremity of the cylinder and the chamber of the crank case, the plate having an offset flange connected with the block whereby the plate is offset by said flange inwardly from the inner end of the cylinder. 40

2. The combination with an internal combustion engine or motor of the V-type, of baffle plates detachably applied to the engine block or frame between the inner extremities of the cylinders and the chamber of the crank case, the plates having attaching flanges offset toward the cylinder whereby the plates are offset inwardly from the cylinders. 45

3. The combination with an internal combustion engine of the multiple-cylinder V-type of baffles, composed of plates whose upper edges are shaped to receive a flange of the engine frame at the inner extremities of

the cylinders, and means for detachably securing the lower ends of the plates to the frame. 55

4. The combination with an internal combustion engine of the multiple-cylinder V-type, of baffles composed of plates whose upper edges are shaped to detachably engage a part of the engine frame at the inner extremities of the cylinders, the lower edges of the plates having openings to receive devices for detachably connecting the plates 60 with the frame. 65

5. The combination with a multiple-cylinder internal combustion engine of the V-type, of baffles detachably applied to the engine frame at the open extremities of the cylinders, and having elongated openings 70 for the piston stems. 75

6. The combination with a multiple-cylinder internal combustion engine of the V-type, of baffles detachably applied to the engine frame at the open extremities of the cylinders, and having elongated openings 75 for the piston stems, these openings being widest at the center, and diminishing in width toward their extremities. 80

7. An oil baffle, comprising a plate having a hook-shaped part at one end adapted to receive a part of the engine frame, and a centering projection adapted to extend between the two cylinders with which the baffle is employed. 85

8. An oil baffle, comprising a plate having openings for the piston stems, and flanges to offset the plate inwardly from the cylinders, a hook for detachably securing the baffle in place and a centering member extending beyond the hook. 90

9. The combination with an internal combustion engine, of a baffle, composed of a plate whose upper edge is shaped to receive a flange of the engine frame at the inner extremity of a cylinder, and means for detachably securing the lower end of the plate to the frame. 95

10. The combination with a multiple-cylinder internal combustion engine, of baffles detachably applied to the engine frame at the open extremities of the cylinders, and having elongated openings for the piston stems. 100

In testimony whereof I affix my signature. 105

GEORGE A. RENDAHL.

It is hereby certified that Letters Patent No. 1,327,779, granted January 13, 1920, upon the application of George A. Rendahl, of Denver, Colorado, for an improvement in "Oil-Baffles for Automobile-Engines," were erroneously issued to Donald P. Hogan, as owner of the entire interest in said invention, whereas said Letters Patent should have been issued to the inventor, said *Rendahl*, and *Donald P. Hogan*, jointly, said Hogan being assignee of *one-half* interest only in said invention, as shown by the record of assignments in this office; and that the said Letters Patent should be read with this correction therein that the same may conform to the record of the case in the Patent Office.

Signed and sealed this 10th day of February, A. D., 1920.

[SEAL.]

M. H. COULSTON,
Acting Commissioner of Patents.
